UNITED STATES PATENT OFFICE.

RICHARD A. CONKLING AND WILLIAM RICHARD GUIBERSON, OF TULSA, OKLAHOMA.

DRILL.

1,281,140.

Specification of Letters Patent.

Patented Oct. 8, 1918.

Application filed January 26, 1918. Serial No. 213,959.

To all whom it may concern:

Be it known that we, RICHARD A. CONKLING and WILLIAM R. GUIBERSON, citizens of the United States of America, residing at 5 Tulsa, in the county of Tulsa and State of Oklahoma, have invented certain new and useful Improvements in Drills, of which the following is a specification.

Our invention relates to an improvement 10 in drills for extracting cores from oil wells.

The requirements of geologists to obtain samples from the underground formations in drilling wells which have not been ground up by the churn drill process, is constantly 15 growing. They have been unable to study the porosity of the sands, the cementation and their character, as well as detect whether it contains fossils or not, due to the fact that all samples had been ground as above mentioned. On account of this we have endeavored to discover some method whereby cores 20 could be removed from wells which were drilled by the Standard or California method. We believe, therefore, that the 25 drill we have devised will accomplish these results.

This drill consists of a core barrel with a drilling face at the bottom or lower end, and having slips inside that are operated by 30 springs to seize the core and remove it intact.

In the accompanying drawings Figure 1, is a longitudinal sectional view, and Fig. 2, is a transverse section.

35 The numeral 1, represents the head of the drill which is adapted to be screwed to the bore of the barrel 10, at its lower end 2, in the usual manner.

The numeral 3, indicates the spring which 40 presses against the slips 4, forcing them

down over the core when it has raised high enough in the barrel 10, to dislodge the pin 5. The pin 5, is inserted through a small hole extending transversely through the barrel of the drill when the slips are raised in 45 order to hold the slips in position until the core is to be extracted. When the core has been cut long enough by the cutting face of the bit marked 6, at its lower end to reach the pin 5, in the slips, then the spring 3, 50 shoves the slip downward in the grooves 8, in the bore of the barrel and the teeth 11, on the ends of the slip engage and tightly embrace the core from opposite sides while the latter is then drawn out, the lower ends 55 of the grooves reducing in depth to cause the teeth to penetrate the core.

The openings 7, in the sides of the barrel let the water in and out as the drill is raised and lowered so that there will be free movement of the drill through the water. 60

The numeral 9, indicates the opening at the lower end which defines the diameter of the core as compared to the size of the bit which will be used. 65

This bit can, of course, be made in all sizes, just as any other drill bits and can be used in a hole of any diameter.

We claim:

A core removing drill comprising a barrel having a bit at one end and a head detachably connected with the other end, slideable spring actuated slips within the barrel, and a pin extending transversely through the barrel for temporarily holding the slips. 70 75

In testimony whereof we affix our signatures.

RICHARD A. CONKLING.
WILLIAM RICHARD GUIBERSON.
